UNITED STATES PATENT OFFICE.

NORMAN O. FLEMING, OF HUNTINGTON PARK, CALIFORNIA, ASSIGNOR TO THE ATMOSPHERIC COOLING CO., INC., OF HUNTINGTON PARK, CALIFORNIA, A CORPORATION OF CALIFORNIA.

COOLING TOWER.

Application filed October 5, 1926. Serial No. 139,607.

My invention relates to cooling towers and particularly to an improved construction for attaching the louvers to the main structure of the tower.

5 The common form of cooling tower consists of a main frame-work which extends upward from a foundation. The main frame-work supports decking over which the water to be cooled may flow, the water being supplied to the cooling tower by means of a suitable supply pipe. In order to prevent the water from leaving the cooling tower and to permit a circulation of air therethrough, louvers are provided which consists of a series of overlapping members which are spaced a distance apart and which slope upward and outward from their inner ends.

10 It is present practice to attach the louvers to the main frame-work by arms which are secured to the main frame-work and extended outward therefrom. The outer ends of these arms are projected through openings formed in the sheathing of the louvers and are secured to cleats which are attached 15 to the sheathing.

15 There are two pronounced disadvantages with the above-mentioned manner of attaching the louvers. First, the cost of assembling is enhanced by reason of the inconvenience of having to project the arms through the openings in the sheathing; secondly, much of the water loss of the cooling tower occurs by reason of water leaking through the openings around the ends of the arms.

20 It is one of the objects of this invention to provide a cooling tower having a construction for attaching the louvers to the frame-work, which construction permits the louvers to be economically attached.

25 It is also an object of this invention to provide a cooling tower having a construction for attaching louvers to the frame-work thereof, which construction requires no openings to be formed in the sheathing of the louver and will therefore reduce water losses.

30 Other objects and advantages will be made evident hereinafter.

Referring to the drawing,

35 Fig. 1 is a plan view of the cooling tower embodying the features of the invention.

40 Fig. 2 is a vertical view of Fig. 1, this view being partially sectioned and being broken away and contracted so as to show the upper and lower ends of the cooling tower.

Fig. 3 is an enlarged fragmentary detail showing the construction which forms the important part of the invention.

Fig. 4 is a section taken on the line 4—4 of Fig. 3.

45 Referring particularly to Figs. 1 and 2, 11 is a foundation which rests within a basin 12. Extended upward from the foundation 11 are vertical posts 14 which are attached together by suitable cross braces 15 and struts 16 as illustrated. These parts of the cooling tower and other parts which are used for forming the main part thereof may be called the main frame-work. The main frame-work supports a series of decking 18 over 50 which the water is passed and broken up so that it may be efficiently cooled. The water to be cooled is supplied to the upper part of the cooling tower by means of a supply pipe 19 having nozzles 20.

55 Supported by the main frame-work of the cooling tower are louvers 25. The louvers 25, as shown in Fig. 1, extend entirely around the main frame-work and as shown in Fig. 2 are arranged in rows which overlap and which are spaced a distance apart. The louvers slant upward and outward from the lower ends thereof so that any water splashing thereagainst cannot escape to the exterior of the tower. The spaces between the louvers 25 permit a free circulation of air 60 which cools the descending water within the cooling tower.

65 The important part of the invention resides in the construction for attaching the louvers to the main frame-work, which construction is illustrated best in Figs. 3 and 4. Referring to these figures, my invention provides arms 26 which are attached to suitable parts of the main frame-work. In the drawing I have shown the arms 26 as being 70 attached to the posts 14 by bolts 27. The arms 26 may be separate parts or they may be formed integral with the other parts of the cooling tower; for example, it would

75 be possible to extend certain of the braces of the main frame-work outward therefrom, utilizing the ends as arms. The arms 26 are projected horizontally outward. The outer ends thereof have faces 28 which rest in the planes parallel to the louvers 25. The louvers 25 consist of sheathings 30 which are braced by louver cleats 31, the louver cleats 31 extending transversely of the sheathings 80

30. The faces 28 of the arms 26 are adapted to fit against inner faces 32 of the sheathings 30.

Attachment of the louvers 25 to the arms 26 is accomplished by means of brackets 34 which are shown as being in the form of angle brackets. The brackets 34 have legs 35 which rest against the sides of the arms 26 and are secured thereto by bolts 37. The 10 brackets 34 also have legs 38 which rest against the inner faces 32 of the louvers 25 and are secured to the louvers by bolts 39. As illustrated best in Fig. 4, the bolts 39 extend through the louver cleats 31 so that a rigid attachment may be obtained. The cleats extend below the sheathings 30 and the lower ends thereof are rigidly supported. In the drawing I show the lower 15 ends of the cleats 31 as being attached by bolts 42 to the inner parts of the arms 26. I find that this is a satisfactory way of attaching the lower ends of cleats but if desired the cleats may be attached to the main frame-work of the cooling tower.

25. In assembling the cooling tower of my invention, the louvers are completely formed on the ground. They are thereafter elevated into their proper positions in which they are then secured. The brackets 34 may 30 be first secured to the arms 26 so that the supporting construction is ready to receive the louver. When the louver is raised in place, the bolts 39 are extended through the legs 38 of the brackets 34 and through the 35 cleats and sheathing of the louver. The louver is thus securely held in place.

The important part of this manner of assembling is that there is no construction work to be done on the louver after it leaves 40 the ground. It is completely formed when it is raised into proper position and the only work necessary at this time is to place the bolts 39. This construction is quite rigid by reason of the fact that the louvers are 45 clamped against the outer bearing faces 28 of the arms 26.

Another prominent advantage of the invention is that no openings are provided in the sheathings 30 of the louvers. This 50 is a marked advantage since it reduces wa-

ter losses of the cooling tower. No openings are required to be formed in the louvers and consequently there can be no leakage through these louvers such as occurs in the ordinary form of cooling tower which requires the openings to be provided in the louvers. 55

I claim as my invention:

1. In a cooling tower the combination of: a main frame-work; decking supported by 60 said main frame-work; means for supplying liquid to be cooled to the upper end of the cooling tower; arms extended outward from said frame-work; louvers located at the outer ends of said arms, said louvers having 65 sheathings and cleats secured to the backs of said sheathings, said louvers sloping upward and outward from the lower ends and said sheathings of said louvers engaging end-faces of said arms which end-faces rest 70 in planes parallel to said louvers; brackets engaging in the upper faces of said sheathings and secured to said arms and said louvers for rigidly securing said louvers to said arms; and means for attaching the 75 lower ends of said cleats each to the next lower arm.

2. In a cooling tower, the combination of a frame-work having outwardly extending relatively spaced arms arranged in vertically spaced tiers; horizontally disposed louvers each positioned adjacent the outer ends of the arms of each tier and each angled to slope upwardly and outwardly from its lower edge, said louvers having 85 sheathings and cleats secured to the under surfaces of said sheathings; means for securing the lower ends of said cleats to said frame-work; brackets secured in contacting relationship to the upper surfaces of 90 the sheathings of said louvers and to said cleats, said securing means extending through said sheathings to engage said cleats; and means for securing said brackets to the respective arms. 95

In testimony whereof, I have hereunto set my hand at Los Angeles, California, this 30th day of September, 1926.

NORMAN O. FLEMING.
